(57) **CLAIM**

The ornamental design for a charging unit, as shown and described.

DESCRIPTION

1. Charging unit

Reproduction 1.1 is a top, front and right side perspective view of a charging unit showing our new design; reproduction 1.2 is a front side view thereof; reproduction 1.3 is a rear side view thereof; reproduction 1.4 is a right side view thereof; reproduction 1.5 is a left side view thereof; reproduction 1.6 is a top view thereof; and reproduction 1.7 is a bottom view thereof; in the reproductions, the broken lines depict portions of the charging unit that form no part of the claimed design.
